(57) CLAIM

The ornamental design for a coating applicator, as shown and described.

DESCRIPTION

FIG. 1 is a perspective view of a coating applicator showing our new design;

FIG. 2 is a side view thereof;

FIG. 3 is a top plan view thereof; and,

FIG. 4 is a bottom plan view thereof.

The broken lines in the drawings illustrate portions of the coating applicator that form no part of the claimed design.
